UNITED STATES PATENT OFFICE.

THOMAS C. BLUE, OF STORM LAKE, IOWA.

DESIGN FOR A DISPLAY-BRACKET.

SPECIFICATION forming part of Design No. 24,968, dated December 10, 1895.

Application filed May 4, 1895. Serial No. 548,162. Term of patent 7 years.

To all whom it may concern:

Be it known that I, THOMAS C. BLUE, a citizen of the United States, residing at Storm Lake, in the county of Buena Vista and State 5 of Iowa, have invented a new and original Design for a Display-Bracket, of which the following is a specification.

This invention relates to a new and original design for display-brackets; and it has 10 for its object to provide a design of this character that shall be both useful and ornamental.

The leading feature of the design resides in a display-bracket shaped to form a triangular 15 figure. The triangularly-shaped figure consists of an upper straight horizontal portion, a lower curved portion, and a vertical portion connecting one end of said upper and lower portions. The upper straight portion of the 20 triangularly-shaped figure is provided at one end with a short upturned angular extremity, and the curved lower portion of said figure touches the upper straight portion near one end, and is provided with a pointed extremity 25 longer than and disposed divergently to the angled extremity of said upper straight portion.

In the drawings, Figure 1 is a perspective

view of a display-bracket embodying the herein-described design. Fig. 2 is a side elevation 30 of a display-bracket embodying the herein-described design.

Referring to the drawings, the numeral 1 designates a display-bracket shaped to form a triangular figure. The triangularly-shaped 35 figure consists of an upper straight horizontal portion 2, a lower curved portion 3, and a vertical portion 4, connecting one end of said upper and lower portions. The upper portion 2 is provided at one end with a short up- 40 turned angular extremity 5, and the lower portion 3 touches the upper portion at the point 6, and is provided with a pointed extremity 7, longer than and disposed divergently to the angled extremity 5. 45

What I claim is—

The design for a display bracket herein shown and described.

In testimony that I claim the foregoing as my own I have hereto affixed my signature 50 in the presence of two witnesses.

THOMAS C. BLUE.
